US00D987701S

(12) **United States Design Patent** (10) Patent No.: **US D987,701 S**
(45) Date of Patent: **** May 30, 2023**

(54) **CAMERA**

- (71) Applicant: **Garmin Switzerland GmbH**, Schaffhausen (CH)
- (72) Inventors: **Nam H. Nguyen**, Kansas City, MO (US); **Derrick D. Lenz**, Olathe, KS (US); **Steven T. Westerkamp**, Gardner, KS (US); **Cole E. Fincham**, Shawnee, KS (US)
- (73) Assignee: **Garmin Switzerland GmbH**
- (**) Term: **15 Years**
- (21) Appl. No.: **29/771,328**
- (22) Filed: **Feb. 22, 2021**
- (51) LOC (14) Cl. **16-01**
- (52) U.S. Cl. **D16/200**
- (58) **Field of Classification Search**
USPC D10/104.1; D12/400; D14/317;
D16/200, 202, 203, 207, 208, 213, 214
CPC .. G03B 2219/00; G03B 19/00; H04N 5/2252;
H04N 2101/00
